FLAT KNITTED STOCKING WELT

Erwin Ruckel, Richmond Hill, N. Y., assignor to
 Louis Hirsch Textile Machines, Inc., New York,
 N. Y., a corporation of New York

Application May 16, 1936, Serial No. 80,028

2 Claims. (Cl. 66—173)

This invention relates to a new and useful improvement in welts for full fashioned stockings knit on flat knitting machines and to a method and mechanism for knitting it.

5 A satisfactory welt must be strong to support the many strains imposed upon it, particularly those radiating from the garter. It must be durable to withstand the wear and tear of the garter and it must also be elastic so that it will fit 10 properly legs of differing sizes.

To secure durability and strength it has been customary to knit the welt of relatively heavy yarn. Since such yarn is less elastic than finer yarns, to secure elasticity or, more correctly, 15 stretchability, it has been the custom to elongate the loops considerably. While this produces a fabric having considerable stretch, it is lacking in all over elasticity with the result that strains, particularly the heavy strains centralized at the 20 points of garter attachment have to be sustained largely by a limited number of loops instead of being well distributed over a considerable fabric area.

One of the main objects of this invention is a 25 welt fabric which automatically adjusts itself to whatever strains are imposed upon it so that they are distributed and absorbed to better effect. As a consequence of this feature the fabric may be made of lighter yarn and smaller loops if desired 30 with consequent improvement in elasticity and without materially reducing durability and strength. Also the elasticity of light yarn small loop construction is of great assistance in properly distributing and absorbing the strains.

35 These features may be obtained by this invention without detracting from the appearance of the welt in any way. In fact the decorative effect is improved. Also the welt may be knit upon a standard flat knitting machine, such as 40 the Karl Lieberknecht machine, without other change than of the narrowing combs and by standard knitting methods.

Another important feature of the welt of this 45 invention is that positive run-stop means is provided which will prevent runs from progressing into the leg. Also that fabric may be reinforced if desired, in the garter section for example, without producing the usual unsightly blocks or patches.

50 The forms of the invention selected for describing the invention herein and one form of modified narrowing points are shown in the accompanying drawings, in which

55 Figure 1 is a view of a welt blank of this invention;

Fig. 2 is a view of the finished welt;
 Fig. 3 is a view of a welt containing a modification of the invention;

Fig. 4 is a greatly enlarged view of the welt of Fig. 2 illustrating diagrammatically the manner in which it behaves when under strain; and 5

Fig. 5 is a view of a type of combined narrowing and lace comb suitable for use in knitting the welt fabric of Figs. 1 and 2.

The welt shown in Figs. 1 and 2 consists of 10 three different kinds of fabric. That of sections 1, 2 and 3 may be of the usual simple loop construction and may be knit, if desired, from yarn of substantially the same weight as that employed in the leg. As already stated, considerably 15 heavier yarns are usually employed in the welt in order to obtain the necessary strength and durability. By using them, however, a great deal of desirable elasticity is sacrificed. By this invention great circumferential elasticity is obtained 20 through the use of much lighter yarns and small loops in the sections 1, 2 and 3. At the same time adequate strength and durability are obtained through the reduction and improved distribution of the strains. The inner edges of sections 1 and 3 are each bordered by a band of lace fabric 25 4 running diagonally across the welt from substantially its outer edge at the top towards the center of the lower edge, as shown in Fig. 1, formed by transferring, say, alternate loops inward by one needle by means of lace points. Inside of and paralleling each of these lace bands are a pair of diagonal bands 5 of fabric, formed 30 by transferring every loop inwardly one needle by means of narrowing points. These bands also 35 run diagonally across the welt and, preferably, meet in a point at the bottom edge. A picot course 10 may also be included to form an attractive loop for the finished welt.

To knit fabric of this construction requires no 40 change in the standard flat knitting machine of the Karl Lieberknecht type, for example, beyond substitution of special narrowing and lace points for those usually employed. A suitable comb is 45 illustrated in Fig. 5. It is provided with the usual narrowing points 6, say eighteen in number, having the same spacing as the needles of the machine followed by a series of lace points 7 spaced according to the lace pattern desired. The particular narrowing comb shown is adapted 50 to work upon the right side of the welt. A corresponding comb is provided for working upon the left side of the welt. These combs are mounted in the usual way upon the usual narrowing rods and are manipulated by the usual narrowing 55

spindles. When the transfer of loops by these combs occurs the loops on the needles corresponding to narrowing points 6 will be transferred inwardly one needle, producing bands 5.

- 5 At the same time the loops upon the needles corresponding to the lace points 7 will also be transferred inwardly one needle producing lace bands 4. The result will be the production of the fabric of Figs. 1 and 2 having two converging bands of fabric composed of closely spaced transferred loops outside of which are two bands of mesh or lace fabric. Because the loops are transferred inwardly the inner margins 8 of bands 5 will form a run stop construction. Therefore, any run 10 which starts in the plain knit area 2 will stop when it reaches the inner margin of either band 5.

The width of bands 5 may be anything desired. A width of approximately eighteen needles has 20 been suggested and shown because then the narrowing points can later be employed, if desired, in the usual way for the usual marginal narrowing of the leg fabric. Thus no change is required after knitting the welt in order that the 25 machine may continue on to the knitting and fashioning of the leg in the usual way.

Aside from this bands 5 can be made as narrow as desired, even to the extent that they become unnoticeable. To do this the number of 30 narrowing points 6 will be correspondingly decreased. Any great decrease in the number of narrowing points, however, may render the combination narrowing and lace point combs unsuitable for use in fashioning the leg. In this case 35 the combination combs should be mounted on their own narrowing rods and so that they can be swung out of the way when not in use, the fashioning of the leg being carried out by other narrowing combs of standard construction and 40 operation.

The fabric of Fig. 3 differs from that of Figs. 1 and 2 only by the omission of diagonal bands 5 so that the fabric sections 1, 2 and 3 are intersected by the lace bands 4 only. This construction 45 also possesses the positive run stop feature at the inner edge 9 of each band because of the superposition of the innermost of the transferred loops upon the outermost of the regular loops of section 2.

For the knitting of this fabric the combination narrowing and lace combs of Fig. 5 are not required. Instead lace combs only having the required number of points to produce the width of lace desired spaced apart so as to be engageable 50 with alternate needles as previously suggested are sufficient. These can be manipulated in the usual way by the usual mechanism to produce the required inward loop transfer.

Any one or as many as desired of plain sections 60 1, 2 and 3 of either form of fabric may be reinforced. For example, in Fig. 3 the lower half of plain section 2 is reinforced to give additional strength to the front outer layer of the welt which is subjected to the greatest strain and the 65 most wear and tear from the pull and attachment of the garter. The lace bands are not only highly decorative in themselves but also frame the reinforcement so that it is barely noticeable.

There is relatively little longitudinal elasticity 70 in plain knit fabric and practically none of it is reinforced. The most severe strains to which a stocking is subjected focus upon the front garter. Not only is the upward pull of this garter severe but it is augmented by increased 75 downward pull whenever the knee is bent. For

these reasons and also because the garter clasp wears or cuts the yarn runs begin with greatest frequency at the point of garter attachment.

Lace fabric is not only elastic in the direction of knitting and at a right angle thereto but also when subjected to diagonal strains has the faculty of adjusting itself to meet them without material wrinkling. Therefore, by the inclusion of lace bands such as 4 elastic and flexible buffer sections are interposed between the plain fabric 10 sections which are able to change their shape in conformity with imposed strains and to transmit these strains back and forth between the plain knit sections. A diagrammatic illustration of the section of the lace sections under the pull of a 15 garter is shown diagrammatically in Fig. 4. It will be noted that the lace sections have become narrow at 11, whereas at 12 they are wider than normal as a result of the difference in direction and strength of the garter pull and other strains 20 upon these two sections. It will also be noted that the transition between the narrowed portions 11 and widened portions 12 are uniform and produce no noticeable wrinkling of the lace or the outlying fabric. Obviously this can result 25 only from a systematically graduated distribution of the strains through the lace sections. Equally obviously the adjacent plain knit sections benefit from this distribution.

The condition depicted by Fig. 4 is, of course, 30 much simpler than that occurring in fact. The actual action of the lace will vary somewhat from that depicted because of the many other strains imposed upon it in many directions, but it will serve to demonstrate how the direct upward pull 35 of the garter which, ordinarily, is imposed largely upon the unreinforced fabric of the upper leg directly below it is turned aside and transmitted to a considerable degree to sections 1 and 3 of the welt which are not only highly elastic but also 40 under much less strain than section 2.

Similarly the very great strains imposed upon the unreinforced leg fabric by bending of the knee are transmitted through the lace to the elastic welt and also the circumferential strains 45 suffered by each section of the welt are transmitted through the lace to the other sections. The lace may be compared roughly to a system of toggles whereby forces acting upon either side of the system and in any direction are equalized, 50 each toggle assuming the position dictated by the resultant forces acting upon it whatever their strength may be or from whatever direction they may come.

It is not essential that the garter section should 55 be reinforced. If it is not it possesses as much inherent elasticity as the sections lying beyond the lace. However, the same toggle action will take place thus relieving the unreinforced garter section of a considerable degree of the normal 60 garter strain, distributing the strain over a greater area and more uniformly and imparting to this section the benefits of the elasticity of the outlying fabric areas.

It will now be evident that the most conspicuous feature of the fabric of this invention is the interposition of lace bands between sections of other character in the welt whereby strains imposed upon one section are more unduly and uniformly distributed and are cushioned by the 70 elasticity of adjacent sections. The arrangements shown are preferred because they also prevent runs originating in any part of the welt, inside the lace bands, from progressing into the leg. However, since the lace also constitutes a part of 75

the decorative design of the stocking it may be desired to change its position and design. This may be done within wide limits without exceeding the scope of the invention. The spacing of the lace points need not be limited to correspond to that of alternate needles but may be made to suit the type of lace desired. Also, the loop transfer need not be limited to the single needle transfer suggested.

10 Also, if desired, the lace bands may be omitted from the fabric of Figs. 1 and 2, the plain bands 5 only being retained. Such a welt is attractive in appearance and possesses the run stop qualities heretofore described, although the benefits derived 15 from the lace bands would, of course, be absent.

I claim:

1. A flat knit welt for a full fashioned stocking composed generally of courses of unreinforced 20 short loops composed of yarn corresponding in character and loop length substantially to the leg and a reinforced area for garter attachment, said reinforced area being framed by and separated from laterally adjacent unreinforced areas

of fabric by sections having greater elasticity and distortability than either the reinforced or unreinforced areas, said sections consisting of bands of lace fabric composed of transferred loops extending diagonally across the welt from substantially the top to bottom. 5

2. A flat knit welt for a full fashioned stocking composed generally of courses of unreinforced short loops composed of yarn corresponding in character and loop length substantially to the leg 10 and a reinforced area for garter attachment, said reinforced areas being framed by and separated from laterally adjacent unreinforced areas of fabric by sections having greater elasticity and distortability than either the reinforced or unreinforced areas, said sections consisting of bands of lace fabric composed of transferred loops extending diagonally across the welt from substantially the top to bottom, said bands of lace also constituting the means for positively preventing 20 runs which originate above said bands from progressing below said bands. 15

ERWIN RUCKEL.
